Patented July 30, 1918.

UNITED STATES PATENT OFFICE.

ALEXANDER C. BEADLE, OF CALUMET, LOUISIANA.

WRENCH.

1,273,989.

Specification of Letters Patent. Patented July 30, 1918.

Application filed June 15, 1915. Serial No. 34,245.

To all whom it may concern:

Be it known that I, ALEXANDER C. BEADLE, a citizen of the United States, residing at Calumet, in the parish of St. Mary and 5 State of Louisiana, have invented a new and useful Wrench; and I do hereby declare the following to be a full, clear, and exact description of the invention such as will enable others skilled in the art to which it appertains to make and use the same.

This invention relates to an improved wrench, and an object of the invention is to provide a wrench involving improved features of construction, namely a movable jaw member movable on a shank, which is provided with a stationary jaw member, the stationary jaw member and the movable jaw member having oppositely disposed rocking jaw plates, which will accommodate themselves to the shape of that which is clamped between them. By providing such locking jaw plates, the teeth of them are enabled to attain a firmer bite into a pipe which is to be turned.

Another feature of the invention is the provision of a movable jaw member having a central opening to receive the shank of the other jaw member and provided with opposite channeled portions, in which tensioned 25 dogs are pivoted, the noses of which extend through openings from said channels, into the central opening, in order to engage the ratchet teeth upon opposite sides of the shank, so as to hold the jaw member in adjusted position. This movable jaw member 30 may be cast in one piece, or may be constructed in several parts, as shown in the drawings.

In practical fields the details of construction may necessitate alterations, falling 40 within the scope of what is claimed.

The invention comprises further features and combination of parts, as hereinafter set forth, shown in the drawings and claimed.

In the drawings:—

Figure 1 is a view in perspective of the improved wrench constructed in accordance with the invention.

Fig. 2 is a longitudinal sectional view, 50 showing parts in elevation.

Fig. 3 is a sectional view on line 3—3 of Fig. 2.

Fig. 4 is a sectional view on line 4—4 of Fig. 2.

Referring to the drawings, 1 designates a shank, having a handle 2 at one end and a

wrench head 3 at the other. One end of the wrench head is provided with a nut engaging surface 4, thereby producing a wrench nut jaw. The other end of the head 3 is reduced as shown at 5, the face 6 of which, is curved as shown in Fig. 2. Engaging the reduced part 7 of the head is a U-shaped jaw plate, having teeth 8, there being a pivot pin 9 extending through the side flanges of the plate and through the reduced part 7, so as to pivot said plate in place. Owing to the surface 6 being curved, as shown in Fig. 2 the jaw plate 8 is permitted to have a slight oscillatory movement, so that the teeth thereof are permitted to firmly bite into a pipe for turning the same. Opposite faces of the shank 1 are provided with ratchet teeth 10 and 11. A movable jaw member 11^a is provided, which comprises the oppositely disposed channel parts 12, the channels 13 of which are open upon opposite sides. One end of each channel part upon its inner face has an opening 14, diagonally opposite a corresponding opening of the opposite channel part. These channeled parts are disposed spaced apart from each other, and upon opposite sides of the shank, with the openings 14 adjacent the ratchet teeth 10 and 11, and are held in such spaced relation by the side plates 15, which are secured to said channel part by the riveted pin 16, and the pins 17, on which the dogs 18 are pivotally mounted. Said plates 15 hold the channeled parts, so as to provide a central opening 19 through the jaw member 11^a, so as to receive the shank 1. One of the channel parts 12 has a lug 20, and portions 21 of the plates 15 are disposed upon opposite sides of the lug 20, but 50 spaced apart therefrom. The lug 20 enters a cavity 22 of the toothed jaw plate 23, which fits between the parts 21 of the plates 15. As shown, the face 24 of the jaw plate 23 is curved, and extending through the parts 21 of the plates 15, and through the lug 20 and the plate 23 is a pivot pin 26, so as to permit the plate 23 to rock, so that its teeth may bite firmly into a pipe to be turned, or so that the surface with said 55 teeth may accommodate itself to the unevennesses of that which is to be turned. It will be observed that the toothed surface of the U-shaped plate 8 of the head 3 is offset beyond the face 4, but upon the opposite side 110 of the wrench. The jaw plate 23 has its toothed surface disposed also beyond the

plane of the nut engaging surface 27 of one of the channel members, so that the toothed surfaces of the U-shaped plate 8 and the jaw plate 23 will engage when a jaw member is moved toward the head. The dogs 18 have their noses 28 extending through the opening 14, in order to engage and ratchet over the teeth 10 and 11. The dogs are also provided with auxiliary noses 28^a to engage the ends 11^b of the channel parts, thereby relieving the shearing actions from the pins 17. The tail ends of the dogs have enlargements 29, protruding beyond the outer edges of the channel members, so that by pressure upon the enlargements, against the action of the springs 30, the dogs 18 will be rocked upon their pivots, sufficiently to disengage their noses from the teeth 10 and 11. The dogs 18 have lugs 31, to engage the coil springs 30, acting to prevent displacement of the springs.

The invention having been set forth, what is claimed as new and useful is:—

The combination with a wrench shank having ratchet teeth on its opposite faces and provided at one end with double wrench jaws, of a double jawed body comprising a pair of opposed central sections spaced to receive the shank therebetween, whereby the sections are arranged adjacent and parallel with the faces of the shank having the

ratchet teeth, a pair of outer plates secured to the sections holding them rigid and parallel to each other, whereby the shank may pass through the space, each of said sections being channeled longitudinally, said channel comprising opposite end walls, side walls, and an inner wall adjacent one of the toothed faces of the shank, the end of the channel remote from the jaws of said body having an opening adjacent the toothed face of the shank, said opening being formed through the inner wall, whereby one end edge of the inner wall forms an abutment shoulder, spring tensioned dogs pivoted in said channels, the noses of the dogs remote from the jaws of the body extending laterally toward each other and through said openings and having shoulders engaging the shoulder walls of the openings to relieve the shearing action on the pivots of the dogs, said noses being in staggered relation and having teeth staggeredly coöperating with the teeth of the shank to hold the body in different adjusted positions.

In testimony whereof I have signed my name to this specification in the presence of two subscribing witnesses.

ALEXANDER C. BEADLE.
